ROBERT CRAIG LAMOND, OF PHILADELPHIA, PENNSYLVANIA, ASSIGNOR TO AMERICAN ENGINEERING COMPANY, OF PHILADELPHIA, PENNSYLVANIA, A CORPORATION OF PENNSYLVANIA.

CONTROL MECHANISM.

Application filed May 10, 1924. Serial No. 712,494.

My invention relates to control mechanism and it has particular relation to such mechanisms as are applicable to limit or reversing devices.

5 In its broad aspect, an important object of my invention is to provide means for automatically operating a limit or reversing device, said means being characterized by its simplicity of design, durableness of construction and positiveness of operation.

10 A more specific object of my invention is to provide controlling mechanism embodying a main control device which is adapted to be tripped and re-set automatically in accordance with the slack in a power-transmitting element.

15 Another object of my invention is to provide a novel system of control comprising a power device, apparatus to be actuated thereby, means for so operatively associating the same that a slack portion appears when the force thereon falls below a predetermined value, control means for said power device, and actuating means for said control means operable in accordance with the variations in said slack.

20 A further object of my invention is to provide means whereby a substantially constant tension may be maintained in an operating cable as a structure secured thereto moves with the rise and fall of a stream.

25 With these and other objects and applications in mind, my invention further consists in the details of construction and operation, hereinafter described and claimed and illustrated in the accompanying drawings, wherein:

30 Fig. 1 is a side elevational view of a ferry bridge and its operating mechanism, illustrating one application of my invention;

35 Fig. 2 is a top plan view of the structure of Fig. 1; and

40 Figs. 3 and 4 are detail side and end elevational views, respectively, of the limit switch operating mechanism.

45 In the illustrated form of embodiment of my invention shown in Figs. 1 to 4, inclusive, a pair of spaced vertically extending frame members 1 and 2 support on their upper ends a pair of spaced horizontally extending members 3 and 4, all of which constitutes a so-called "gallows frame" which is mounted on a suitable supporting structure or foundation 5 positioned near the outer end of a 50 ferry bridge 6, the inner end of which may

be hinged to a supporting structure (not shown) in the usual manner, whereby the outer end of the bridge 6 may be moved vertically, at will, or in accordance with the rise and fall of a body of water.

55 A desired portion of the weight of the outer end of the ferry bridge 6, say, for example, 95%, may be counter-balanced by weights 7 and 8 which are respectively hung from the cables 9 and 11. The cables 9 and 11 respectively pass over sheaves 12 and 13, which are mounted on the upper supporting frame work 3-4, and extend downwardly to dead-end supporting elements 14 and 15 secured on the opposite sides of the ferry 60 bridge 6.

65 The outer end of the bridge 6 may be raised and lowered, at will, by means of an electric motor 16 having an operative connection through suitable gearing 17-18 with a winding drum 19 which is preferably disposed in proximity to the center of the upper supporting structure 3-4. The motor 16 may be manually controlled by means of a controller of the usual type and associated circuits (not shown), wherein opposite movements of the controller from a neutral position cause the respective energization of said circuits and consequent reversals in the direction of operation of the 70 winding drum 19.

75 Cables 21 and 22 respectively extend in opposite directions from the winding drum 19 over sheaves 23 and 24, which are mounted on the upper supporting structure 3-4, and under sheaves 25 and 26, which are secured by sheave saddles 28 to the opposite sides of the ferry bridge 6. From the sheaves 25 and 26, the cables 21 and 22 pass upwardly and over sheaves 29 and 31, which are mounted on the upper supporting structure 3-4, then down under traveling sheaves 32 and 33, respectively terminating on dead-end supporting elements 34 and 35. The traveling sheaves 32 and 33 may be 80 revolvably mounted on shafts 36-36, the ends of which are vertically guided by pairs of spaced members 37 and 38 (Figs. 3 and 4).

85 When it is desired to raise the outer end of the hinged bridge 6, the controller for the driving motor 16 is moved into the raising position, thereby causing the drum 19 to absorb or decrease the slack in the cables 21 and 22 and finally resulting in the actua- 100 105 110

tion of the sheaves 32 and 33 into their upper maximum position shown in Fig. 1. The continued operation of the winding drum 19 then causes the lifting of the outer 5 end of the hinged bridge 6 and this movement continues so long as the motor controller is held in the raising position.

When the motor controller is actuated into the lowering position, the drum 19 moves 10 to unwind the cables 21 and 22, so that the outer end of the hinged bridge 6 is lowered until strong backs 39 and 40, which extend from the outer end of the bridge 6, rest on the deck of the boat to be moored 15 (not shown). Assuming that the controller is retained in the lowering position, the driving motor 16 continues to unwind the cables 21 and 22, causing the same to become slack since the load of the bridge 6 20 has been removed therefrom. As hereinbefore noted, my invention contemplates means for centralizing the slack appearing in the cables 21 and 22 and it further contemplates an automatic limit switch 41 25 adapted to be operated in accordance with the variations in the length of the slack portion of one of the cables 21 and 22, say the latter, whereby the driving motor 16 may be automatically controlled. To this 30 end, I provide the above-mentioned traveling sheaves 32 and 33 which are so weighted that they centralize such slack as may appear in the cables 21 and 22.

The automatic limit switch 41 (Figs. 3 35 and 4) for effecting the above-noted desired result includes trip mechanism 42 which is operatively associated with the traveling sheave 33 only. The trip mechanism 42 is so related to the limit switch 41 that the solid 40 and dot-and-dash line positions thereof in Fig. 3 represent open and closed switch positions, respectively. The trip mechanism 42 comprises a switch-operating shaft 43 which provides a mounting for a member 44 45 having oppositely extending arms 45 and 46. The operating member 44 is caused to move normally into the circuit closing dot-and-dash line position by a weighted member 47 carried on the outer end of the 50 arm 45.

The movement of the switch-operating member 44 from the open solid-line position to the closed dot-and-dash line position may be prevented by means of a locking lever 48 55 pivotally mounted on an upper side of the arm 46. The locking lever 48 releasably engages a shoulder 49 formed on one of the movable sheave guides 38 with a force proportional to that of the said weighted member 47. The locking lever 48 may be actuated clear of the retaining shoulder 49 by means of a releasing lever 51 which is rigidly secured to a shaft 52 common to the locking lever 48. The releasing lever 51 is preferably weighted so that the locking lever 48

may be normally returned from an ineffective position, which it assumes when it is actuated clear of the shoulder 49, to the effective position shown in solid-line in Fig. 3 of the drawing. The releasing lever 51 is 70 of such length that it may be engaged by an operating pin 53, which projects from one end of the sheave shaft 36, only when the latter is moved vertically upwardly and the switch-operating member 44 is in the 75 locked circuit-opening position. The releasing lever 51 and the locking lever 48 may be retained in the dot-and-dash line position by means of a lug 54 on the member 44 which engages a shoulder 55 formed on the 80 releasing lever 51.

When the operating pin 53 is moved downwardly in accordance with an increase in the slack of the cable 22, the pin 53 finally engages a projecting portion 56 of the 85 arm 46, causing the switch-operating member 44 to move from the circuit-closing position shown in dot-and-dash lines in Fig. 3 to the circuit-opening position, shown in solid-line. In order that the operating pin 90 53 may pass by the extension 56 when moved vertically upwardly without causing the operation of the member 44, I pivotally mount the extension 56 on the outer end of the arm 46 and provide a projecting lug portion 95 57 on the member 56 which is adapted to engage a shoulder 58 formed on the under side of the member 44.

In operation, assuming the traveling sheaves 32 and 33 at the upper limit of their 100 stroke and the switch-operating member 44 in its circuit-closing position, a movement of the motor controller into the lowering position causes a downward movement of the outer end of the bridge 6 until the strong backs 39 and 40 thereof rest on the boat or other apparatus (not shown) to be moored to the ferry bridge 6. The continued operation of the motor 16 thereupon causes slack in the cables 21 and 22 which 105 is centralized by the weighted guiding sheaves 32 and 33. As the slack in the cables 21 and 22 increases, the sheaves 32 and 33 move downwardly, finally resulting in the operating pin 53 engaging the hinged arm 110 56 and actuating the movable member 44 from the circuit-closing position to the locked circuit-opening position shown in solid-line in Fig. 3, whereupon the motor 16 115 becomes inoperative.

When the operating controller of the motor 16 is moved into the raising position, the motor 16 immediately becomes effective to cause the drum 19 to absorb the slack in the cables 21 and 22, thereby resulting in an upward vertical movement of the sheaves 32 and 33 as well as the operating pin 53. Since the projecting arm 56 is so mounted on the arm 46 of the switch-actuating member 44 that it may be actuated upwardly 125 130

independently of the latter, the pin 53 moves upwardly without disturbing the member 44 until it engages the releasing lever 51.

The continued upward movement of the pin 53 causes the releasing lever 51 to move upwardly, thereby actuating the locking lever 48 out of engagement with the retaining shoulder 49. The switch-operating member 44 now moves under the force of the weighted member 47 from the circuit-opening position to the circuit-closing position, the hinged extension 56 being correspondingly moved upwardly into a position where it may be again engaged by the operating pin 53 upon a downward movement of the same. The sheaves 32 and 33 continue their upward movement until they reach the limit of their stroke, whereupon the outer end of the bridge 6 is raised. When the outer end 20 of the ferry bridge 6 is raised to the desired height, the controller of the driving motor 16 is actuated from the raising position to the neutral position to hold the bridge 6 in the desired position. If the motor controller 25 is again moved into the lowering position, the foregoing cycle is repeated, the operating-pin 53 again actuating the switch-operating lever 44 from the circuit-closing position to the locked circuit-opening position, 30 to effect the inoperation of the driving motor 16.

A further valuable feature of my invention is the maintaining substantially constant over a long period of time the tension 35 in the cables 21 and 22, regardless of a fall in tide. To effect this desired result, the controller of the motor 16 is moved into the lowering position, causing the bridge 6 to fall until the strong backs 39 and 40 engage the deck of a boat to be moored. The continued operation of the motor 16 causes the drum 19 to unwind until the pin 53 engages the switch-operating lever 44, actuating the latter from the circuit-closing position 40 to the circuit-opening position, whereupon the motor 16 becomes ineffective.

As the boat and ferry bridge 6 continue to descend with the falling tide, the traveling sheaves 32 and 33 and, consequently the pin 53, move upwardly until the latter engages the lock releasing lever 51, permitting the weighted member 47 to actuate the switch-operating member 44 into its circuit-closing position. The motor 16 then continues to unwind until the pin 53 is again moved downwardly sufficient to cause a movement of the switch-actuating member 44 to the circuit-opening position. This cycle continues so long as the bridge 6 descends with the tide. In arranging my apparatus for rising tides, the controller for the motor 16 is moved into the raising position and the pairs of traveling sheave guides 37 and 38 are made of such length that the sheaves 32 and 33 may descend an amount sufficient

to accommodate for the maximum high tide.

While I have shown only one form of embodiment of my invention, for the purpose of describing the same and illustrating its principles of construction and operation, it is apparent that various changes and modifications may be made therein, without departing from the spirit of my invention as for instance the use of any form of slack operated controlling device or the power source 16. I desire, therefore, that only such limitations shall be imposed thereon as are indicated in the appended claims or as are demanded by the prior art.

I claim:

1. A power device, bridge apparatus to be actuated thereby, means including a cable for operatively associating said device and said bridge apparatus, means for centralizing the slack in said cable appearing when the strain in the latter falls below a predetermined value, control means, and means whereby said slack may operate said control means.

2. Bridge operating mechanism comprising a power device, bridge apparatus to be actuated thereby, means including a cable for so operatively associating said device and said bridge apparatus that a slack portion appears in said cable when the strain therein falls below a predetermined value, control means, and an actuating element for said control means responsive to variations in said slack portion.

3. A power device, a movable bridge, a cable for operatively associating said device and said bridge, weighted guiding means for centralizing the slack in said cable appearing under predetermined operating conditions, and control means adapted to be actuated in accordance with variations in said slack, said control means determining the effectiveness of said power device.

4. In a system of control for a ferry bridge, the combination with a power device and bridge apparatus adapted to be actuated thereby, of means including a cable for operatively associating said device and said bridge apparatus, weighted means for centralizing the slack in said cable appearing when the strain in the latter falls below a predetermined value, and control means responsive to variations in said slack.

5. In combination, a power device, a movable bridge means including a cable for operatively associating said device and said bridge, a traveling sheave adapted to centralize the slack in said cable appearing under predetermined operating conditions, control means for said power device, and operating mechanism for said control means adapted to be tripped and re-set by said traveling sheave, whereby said power device may be successively rendered ineffective and effective.

6. A system of control comprising a power device, a ferry bridge means including a cable for operatively associating said device and said ferry bridge, weighted means 5 for centralizing the slack appearing in said cable under certain operating conditions, control means for said power device, and mechanism for actuating said control means in accordance with the direction of movement of said weighted means.

7. Apparatus of the class described comprising a bridge structure to be moved, a power device, a cable for operatively associating said bridge structure and said device, 15 a traveling sheave movable in accordance with the slack appearing in said cable under certain conditions of operation, and a controlling device for said power device adapted to be operated by said traveling 20 sheave.

8. In combination, a structure to which a boat is to be moored, a driving drum, power-transmitting means including a cable operatively associating said structure and said 25 drum, and means operable in accordance with the movement of said drum for controlling the operation of the latter.

9. A structure positioned to fall with the tide, a power device, cable means operatively 30 associating said device and said structure, whereby the latter may be lowered independent of the tide, and means controlled by said cable means for automatically maintaining a predetermined slack in said cable means as 35 said structure falls with the tide.

10. In combination, a structure positioned to rise with the tide, a power device, lifting cables operatively associating said device and said structure, and means whereby the 40 amount of slack in said cable may be maintained within certain limits as said structure rises with the tide.

11. A system for a ferry bridge comprising a sheave movably mounted in spaced guides, a control member movable from one position to another, means for exerting a force on said control member tending to move the latter from one of said positions to another, locking means for releasably retaining said member in one of said positions, one of said guides constituting retaining means for said locking means, and releasing means positioned to be actuated by said sheave when said sheave is moved in one direction only.

12. Bridge control mechanism comprising a sheave movably mounted in spaced guides, a pivoted member provided with oppositely extending arms, means for exerting a force on one of said arms, a locking lever movably positioned on the other of said arms, one of said guides being provided with a retaining shoulder for said locking lever, and a releasing lever for said locking lever positioned to be actuated by said sheave when the latter is moved in one direction, said member being actuated by said sheave when the latter is moved in another direction.

13. In combination, a power device, a movable bridge adapted to be actuated thereby relative to a supporting surface, means including a cable for operatively associating said device and said bridge, whereby the latter may be actuated relative to said surface, said cable having a slack portion appearing upon the continued operation of said power device after said bridge has engaged said supporting surface, a controlling device for said power device, and means whereby said slack portion may control said power device.

ROBERT CRAIG LAMOND.
